CLAIM

The ornamental design for a negative pressure apparatus module, as shown and described.

DESCRIPTION

FIG. 1 is a top and front isometric view of a negative pressure apparatus module, shown in an environment of use; FIG. 2 is a bottom and front isometric view thereof; FIG. 3 is a front elevation view of the negative pressure apparatus module;

FIG. 4 is a right side view thereof;

FIG. 5 is a left side view thereof;

FIG. 6 is a bottom plan view thereof;

FIG. 7 is a bottom and front isometric view thereof; and,

FIG. 8 is a top and rear isometric view thereof.

The broken line showing of the negative pressure apparatus in FIGS. 1-2 depicts environmental structure and forms no part of the claimed design. All other broken lines in the drawings depict portions of the negative pressure apparatus module that form no part of the claimed design.
